CHARLES Q. LUCKE, OF CHICAGO, ILLINOIS, ASSIGNOR OF ONE-HALF TO J. H. KIMMONS,
OF CHICAGO, ILLINOIS.

PORTABLE FIREPROOF BUILDING.

950,140.

Specification of Letters Patent. Patented Feb. 22, 1910.

Application filed March 22, 1909. Serial No. 485,056.

To all whom it may concern:

Be it known that I, CHARLES Q. LUCKE, a citizen of the United States of America, residing at Chicago, in the county of Cook 5 and State of Illinois, have invented a new and useful Portable Fireproof Building, of which the following is a specification, reference being had to the accompanying drawings, illustrating same.

10 My invention relates to buildings, and more in particular to the construction of cement or concrete buildings from blocks, the principal objects of the invention being to provide an improved block-building which 15 is fireproof and which may be readily and easily taken to pieces and transported to any suitable place and then readily rebuilt; to provide an improved block-building which may be readily changed in its construction, 20 or remodeled, as desired; to provide an improved construction for the walls of such buildings; to provide an improved construction for the door casings and window casings in such buildings; and to provide an 25 improved construction in the various parts of such buildings.

Other objects will be apparent from the following specification.

In cement or concrete houses or buildings 30 heretofore constructed, it is not easy to take such houses or buildings apart, transport the parts to some other locality and then reconstruct the house or building. In the present invention this can be readily done, 35 as the building is constructed of blocks and parts which are rigidly and substantially locked together without the use of mortar, and which at the same time permit of being disassembled when desired and then being 40 reassembled as at first.

By the aid of this present invention a house may be built and then later remodeled or changed in size as desired, by the addition of a small number of new parts, practically all of the old parts being usable in the new form of the house. Thus a house or 45 building may be reconstructed at a very little cost, there being practically no waste of material.

50 Another advantage of this invention is that it does not require skilled labor to construct a house or building in accordance with the present invention, or in other words to place the blocks together, the various blocks 55 and parts being molded or formed, and num-

bered if desired, so that it can be readily seen where they belong in the structure. This advantage makes the first cost of a building very small, because a great item of expense in the form of skilled labor is eliminated. 60

I will now describe the invention more in detail by reference to the accompanying drawings, in which—

Figure 1 is a perspective view of a portion of the wall-construction of a building constructed in accordance with this invention, with portions shown in cross-section, showing the interlocking of the various blocks; Fig. 2 is a perspective view of a portion of the wall shown in Fig. 1, with a portion shown in cross-section, showing the relative positions of the interior and exterior wall blocks; Fig. 3 is a perspective view of a door or window casing constructed in accordance with this invention, showing its relation with the wall blocks; and Fig. 4 is a perspective view of the top door or window casing used in connection with a pair of side door or window casings shown in Fig. 3. 80

Like characters refer to like parts in the several figures.

The wall blocks 6 6, preferably made of cement, concrete, or terracotta, are hollow as shown at 7 7 in Fig. 1. Within the outer wall 85 blocks 6 6 are placed hollow inner wall blocks 8 8, preferably made of cement, concrete, or terracotta, as shown in Figs. 1 and 2, the joints 9 9 between the outer wall blocks coming midway along the inner wall blocks 8 8 90 and the joints 10 10 between the inner wall blocks coming midway along the outer wall blocks 6 6, preferably as shown in Figs. 1 and 2. The upper and lower edges of the outer wall blocks preferably overlap each 95 other as shown at 11 11 in Fig. 1. The outer wall blocks 6 6 of each horizontal row are interlocked by means of tongue and groove connections as shown in Fig. 1, each block 6 being provided on one side with a vertical tongue 12 and on the opposite side with a vertical groove 13. This interlocking of the outer wall blocks, and their overlapping as at 11 11, makes a wall constructed in this manner absolutely wind and moisture 100 proof. The double construction of the wall by means of the outer blocks 6 6 and inner blocks 8 8, gives an exceedingly solid construction to such a wall, without the aid of mortar, and takes any undue strain caused 105 110

by a side pressure on the wall, off of the tongue portions 12 12. Both the outer wall blocks 6 6 and the inner wall blocks 8 8 are provided with holes 14 14 through the sides 5 thereof, the holes in the inner wall blocks registering with the holes in the outer wall blocks whereby a continuous air passage is provided throughout the entire wall of a building. This air passage throughout the 10 wall makes same a poor conductor of heat, and therefore provides a wall through which extreme heat or cold does not readily pass. The lower horizontal row of wall blocks 6 6 may fit over suitable portions of a foundation, the lower row of inner wall blocks 8 8 resting on top of the said portions of the foundation. At the top of a wall, short inner wall blocks are preferably used.

In constructing a chimney, one vertical 20 row of outer and inner wall blocks may be used. In such a chimney there are preferably no holes 14 14 in the blocks.

The tiers of wall blocks along the sides of the doors and windows of a building are 25 preferably constructed as shown in Fig. 3, the door or window casing 16 fitting in a vertical groove 17 in the tier of wall blocks 6^a 6^a as shown in Fig. 3. The exterior portion of the casing or casings 16 may be covered with wood strips if desired. The strip 16 is preferably an iron strip. Across the top of the door or window is placed an iron bar or strip 18 shown in Fig. 4, the ends of the bar 18 being dovetailed as at 19 19 to 35 fit into the grooves 17 in the wall blocks 6^a 6^a, on top of the side casings 16. The door sill or window sill may be a cement or concrete block, the door sill preferably coming about level with the floor of the building.

40 I wish it to be understood that the extent of the parts of such a building as is herein described, may be whatever is desired, the invention in no way being limited to any certain size of building. With various buildings of course additional rows or tiers of the various blocks or parts may be employed.

I do not wish to be limited to the exact material herein specified, for the blocks or parts of a building coming under this invention. I also wish it to be understood that various parts of the building may be ornamented as desired. Neither do I wish to limit this invention to all of the particular details herein set forth, as various modifications of the same may be made without departing from the scope of the appended claims.

What I claim as my invention is:

1. A building of the character described 60 having a wall constructed of horizontal rows of hollow outer blocks, the blocks of each row having integral tongue and groove in-

terlocking relation with each other, some of the outer and inner horizontal edges of the said blocks being recessed therealong and some of the said edges being extended to fit in the adjacent said recesses whereby the blocks of the adjacent said rows have overlapping relation with each other along their outer and inner horizontal edges, and a plurality of inner blocks carried within the said outer blocks, the joints between the said inner blocks being disposed medially regarding the said outer blocks. 65

2. A wall of the character described comprising horizontal rows of hollow outer blocks having vertical tongue and groove interlocking relation with each other the blocks of the adjacent rows having horizontal overlapping relation with each other along their 70 inner and outer edges, and a plurality of hollow inner blocks carried within the said outer blocks, the horizontal joints between the said inner blocks being alternately disposed with the horizontal joints of the said 75 outer blocks, all of the said blocks having registering openings through some of the sides thereof whereby a continuous air passage is formed throughout the wall. 80

3. A wall of the character described comprising hollow outer blocks having integral tongue and groove interlocking relation with each other, some of the outer and inner edges of the said blocks being recessed and some of the said edges being extended to fit 85 in the adjacent said recesses whereby the said blocks have overlapping relation with each other along their outer and inner edges, and a plurality of inner blocks carried within the said outer blocks, the joints between the 90 said inner blocks being disposed medially regarding the said outer blocks, for purposes substantially as described. 95

4. A wall of the character described comprising rows of hollow outer blocks having 100 integral tongue and groove interlocking relation with each other, the blocks of the adjacent rows having overlapping relation with each other along their inner and outer edges, and a plurality of hollow inner blocks carried within the said outer blocks, the joints between the 105 said inner blocks being medially disposed regarding the joints between the said outer blocks, all of the said blocks having registering openings through some 110 of the sides thereof whereby a continuous air passage is formed throughout the wall. 115

As inventor of the foregoing I hereunto subscribe my name, this 16th day of March, 1909.

CHARLES Q. LUCKE.
